UNITED STATES PATENT OFFICE

JANET M. KNOPF, OF NEW YORK, N. Y.

DESIGN FOR A RIDING STICK TOY

Application filed March 4, 1932. Serial No. 43,081. Term of patent 7 years.

To all whom it may concern:

Be it known that I, JANET M. KNOPF, a citizen of the United States, residing at No. 220 West 98th Street, borough of Manhattan, State of New York, have invented a new, original, and ornamental Design for a Riding Stick Toy, of which the following is a specification, reference being had to the accompanying drawing, forming part thereof.

In the drawing,—

Figure 1 is a perspective view of a riding stick toy embodying my new design;

Figure 2 is a side view of the toy; and
Figure 3 is a front end view thereof.

I claim:

The ornamental design for a riding stick toy as shown.

JANET M. KNOPF.
